UNITED STATES PATENT OFFICE.

EMMITT A. TAPLEY, OF CHICAGO, ILLINOIS, ASSIGNOR OF ONE-HALF TO
DANIEL W. SCOTT, OF SAME PLACE.

DESIGN FOR A MUSICAL-INSTRUMENT BODY.

SPECIFICATION forming part of Design No. 32,613, dated May 1, 1900.

Application filed November 27, 1899. Serial No. 738,485. Term of patent 7 years.

To all whom it may concern:

Be it known that I, EMMITT A. TAPLEY, a citizen of the United States of America, and a resident of Chicago, in the county of Cook and State of Illinois, have invented a new and original Design for a Musical-Instrument Body, of which the following is a specification, reference being had to the accompanying drawings, forming a part thereof.

10 In the drawings, Figure 1 is a front elevation of the body of a musical instrument made according to my new design. Fig. 2 is a side elevation of same.

The leading or material feature of my design consists in the body of the instrument in the form of an ellipse, said body being of uniform depth throughout and having a sounding-hole in the form of an ellipse centrally located in the upper half of the front

of the body, with its minor axis in alinement 20 with the major axis of said body.

In the drawings, 1 represents the body. 3 is the front, and 3' is the back of same.

4 is the sounding-hole located in the upper half of the front 3. 25

The reference-numerals 6 to 10, inclusive, represent marks on the front 3.

What I claim as new, and desire to secure by Letters Patent, is—

The design for a musical-instrument body, 30 substantially as shown and described.

Signed by me at Chicago, Illinois, this 25th day of November, 1899.

EMMITT A. TAPLEY.
